UNITED STATES PATENT OFFICE.

ELMER QUICK, OF WEST TULSA, OKLAHOMA, ASSIGNOR OF ONE-HALF TO JAY GOULD
WATTS, OF WEST TULSA, OKLAHOMA.

COLLAPSIBLE BASIN.

1,334,260.

Specification of Letters Patent. Patented Mar. 16, 1920.

Application filed June 22, 1918. Serial No. 241,381.

To all whom it may concern:

Be it known that I, ELMER QUICK, a citizen of the United States, residing at West Tulsa, in the county of Tulsa and State of Oklahoma, have invented new and useful Improvements in Collapsible Basins, of which the following is a specification.

In field hospitals, camps and other places where floor space is limited and ease of transportation a very important factor, desirability of a collapsible basin for washing purposes is pronounced. It is our purpose to produce such a structure, in which a basin constructed of a suitable water-proof fabric may be easily, quickly and securely attached to a collapsible frame or support, and wherein both the basin and the support may be folded into a small package for easy transportation, when not in use.

Other objects and advantages of the improvement will appear as the nature of the invention is better understood, reference being had to the accompanying drawings, in which—

Figure 1 is a perspective view of my improvement in its set-up condition.

Fig. 2 is a detail elevation showing the manner in which two of the hingedly connected sections of the device are held in longitudinal alinement.

Fig. 3 is a sectional view approximately on the line 3—3 of Fig. 1.

Fig. 4 is a detail horizontal sectional view through one of the corners of the device in set up position.

Fig. 5 is a perspective view of the device, collapsed.

Fig. 6 is a plan view of the removable and collapsed basin.

My improvement contemplates the employment of a substantially rectangular frame. The frame includes four corner posts or legs each of which is indicated by the numeral 5. To the inner face of the legs 5 at the upper corners thereof are hingedly secured, as at 6, brace members 7, and these brace members provide the top of the frame. Each of the braces 7 is in the nature of two links which have their confronting ends connected by rule joints 8. This permits of the links being folded downwardly of the frame between the legs 5 thereof but holds the links horizontally with

respect to the frame, when the same are in their spread position. One of each of the 55 respective pairs of links is provided with a 60 sliding bolt 9 that is adapted to be received in a keeper 10 in the coacting link, and, of course, when the bolts are raised in the keepers the links are sustained in alinement. 65 Each pair of links, to the opposite sides of their hinged connections 8, is provided with an outstanding stud 11.

In addition to the brace members 7, which, as stated, provide the top of the frame, the 65 legs 5, at a suitable distance above the bottom of the frame, have hingedly secured upon their confronting faces, as at 12, brace members 13. These brace members each include a pair of links, the confronting faces of 70 which being connected by rule joints 14 which permit of the links being swung upwardly of the frame, but which hold the links in proper alinement when the same are brought to operative position. 75

With a structure as above described, it will be seen that the frame, by folding the links comprising the brace members between the legs thereof, may be readily collapsed to provide a small package, and as the frame is of 80 a comparatively small light structure the same may be readily conveyed from place to place as desired, or will occupy only a small space for storage or shipment. Each of the legs 5 has pivotally connected thereto, a considerable distance above the lower end thereof, a brace rod 21. Each of the rods, at its ends opposite its pivotal connection 22 with the respective legs 5 has an offset or angle portion 23. Each of the legs 5, upon the angle side thereof opposite that provided with the pivot 22, and at a considerable distance above the pivot is provided with an eye 24 to receive the angle or hook-shaped end of the brace rod 21 secured to the oppositely 95 disposed leg. In this manner the frame is more effectively sustained in its set up condition. When in collapsed condition the brace rods 21 will fold between the angle portions of the legs 5, it being noted that the 100 said legs are constructed of angle members.

The basin is indicated by the numeral 15 and is formed of some water-proof fabric. To the central portion of the basin is secured what may be termed the rim, which is indicated by the numeral 16. The rim is 105

formed from a flat sheet of material similar to that from which the basin proper is formed, and this rim, at its corners, and centrally between its corners, is provided with 5 extensions or tabs 17, 18, respectively. The central tabs 18 are provided with eyelets or openings 19 arranged in pairs and adapted to engage with the studs 11 which project outwardly from the upper links or brace members 7. The corner tabs 17 are likewise provided with eyelets or openings which engage headed studs 20 on the legs 5, at the upper portions thereof.

By a construction of a basin as above described, it will be seen that the same may be easily and quickly attached to or removed from the frame. When secured upon the frame, the tabs connecting with the studs on the said frame reinforce the frame and, as 10 illustrated in Fig. 6 of the drawings, it will be seen that it is not necessary to remove the basin from the frame when the frame is collapsed. It is, of course, desirable that the basin be in the nature of a removable 15 member so that water may be emptied therefrom and the basin cleaned when necessary,

Having thus described my invention I claim:—

In a device for the purpose set forth, a collapsible frame having corner members constructed of angle irons, lower brace members having their confronting ends provided with hinge joints and their outer ends pivotally secured to the angle irons, upper brace members having their confronting ends provided with hinge joints opening in an opposite direction from the lower hinge joints, pivoted connecting means between the last mentioned brace members and the upper corners of the legs, slidably latching means 30 in longitudinal alignment, brace rods pivoted to the respective leg members and removably engaging the oppositely disposed leg members, and a fabric basin designed to be supported upon the top of the frame and 35 having tab members connected with the frame, certain of which overlie the slidably latching means for the upper brace members.

In testimony whereof I affix my signature. 40

ELMER QUICK.
